(57) **ABSTRACT**

A golf club head has a face portion, a crown portion, and a sole portion. The golf club head includes a weight member that is configured to be wound, a first wound portion around which a first part of the weight member is to be wound, and a second wound portion that is disposed apart from the first wound portion and around which a second part of the weight member is to be wound. In the golf club head, a position of a center of gravity of the golf club head is adjusted by changing a weight ratio of the first part to the second part. At least either the first wound portion or the second wound portion may be rotatable in a reel-in direction and a reel-out direction.

GOLF CLUB HEAD

CROSS REFERENCE TO RELATED APPLICATION

The present application claims priority to Japanese Patent Application No. 2021-041039 filed on Mar. 15, 2021. The entire contents of this Japanese Patent Application are hereby incorporated by reference.

BACKGROUND

Technical Field

The present disclosure relates to a golf club head.

Description of the Related Art

There has been known a golf club head in which the position of the center of gravity of the head can be adjusted. JP2011-010722 A discloses a golf club head including a weight body that can move on a guide groove.

SUMMARY

The inventor of the present disclosure has found a new structure capable of adjusting the position of the center of gravity of a head. This new structure exhibits new advantageous effects brought by the structure.

The present disclosure provides a golf club head having a new structure that includes a mechanism of adjusting the center of gravity of the head.

In one aspect, a golf club head according to the present disclosure includes a face portion, a crown portion, and a sole portion. This head includes a weight member that is configured to be wound, a first wound portion around which a first part of the weight member is to be wound, and a second wound portion that is disposed apart from the first wound portion and around which a second part of the weight member is to be wound. The position of a center of gravity of the head is adjusted by changing a weight ratio of the first part to the second part.

BRIEF DESCRIPTION OF THE DRAWINGS

FIG. 1 is a plan view of a head according to a first embodiment;

FIG. 2 is a bottom view of the head in FIG. 1;

FIG. 3A is a cross sectional view taken along line A-A in FIG. 2, FIG. 3B is a cross sectional view taken along line B-B in FIG. 2, and FIG. 3C is a cross-sectional view taken along lines C-C in FIG. 3A and FIG. 3B;

FIG. 4A is a cross-sectional view of a first wound portion b1 and its vicinity according to a first modification example, FIG. 4B is a cross-sectional view of a second wound portion b2 and its vicinity according to the first modification example, and FIG. 4C is a cross-sectional view taken along lines C-C in FIG. 4A and FIG. 4B;

FIG. 5A and FIG. 5B are cross-sectional views of a first wound portion b1, a second wound portion b2 and their vicinity according to a second modification example, and also shows cross-sectional views taken along line A-A and line B-B, the first wound portion b1 (second wound portion b2) in FIG. 5A being situated at a pushed-in position, and the first wound portion b1 (second wound portion b2) in FIG. 5B being situated at a projecting position;

2

FIG. 6 is a cross-sectional view showing an alternate mechanism according to the second modification example;

FIG. 7 is a bottom view of a head according to a second embodiment;

5 FIG. 8 is a bottom view of a head according to a third embodiment;

FIG. 9 is a bottom view of a head according to a fourth embodiment;

10 FIG. 10 is a bottom view of a head according to a fifth embodiment;

FIG. 11 is a bottom view of a head according to a sixth embodiment;

FIG. 12 is a bottom view of a head according to a seventh embodiment;

15 FIG. 13A is a plan view of a head according to an eighth embodiment, and FIG. 13B is a bottom view thereof;

FIG. 14 is a plan view of a head according to a ninth embodiment;

20 FIG. 15A is a plan view of a head according to a tenth embodiment, and FIG. 15B is a bottom view thereof;

FIG. 16A is a plan view of a head according to an eleventh embodiment, and FIG. 16B is a bottom view thereof;

FIG. 17 is a bottom view of a head according to a twelfth embodiment;

25 FIG. 18A is a cross sectional view taken along line A-A in FIG. 17, FIG. 18B is a cross sectional view taken along line B-B in FIG. 17, and FIG. 18C is a cross-sectional view taken along lines C-C in FIG. 18A and FIG. 18B;

FIG. 19 is a perspective view showing a toothed surface 30 forming a locking and tightening mechanism that is an example of a rotation regulating mechanism;

FIG. 20 is a side view of the locking and tightening mechanism including the toothed surface in FIG. 19; and

35 FIG. 21 is a conceptual diagram for illustrating a toe-heel direction and a face-back direction.

DESCRIPTION OF THE PREFERRED EMBODIMENTS

40 Hereinafter, embodiments will be described in detail with appropriate references to the accompanying drawings.

In the present disclosure, a reference state, a reference perpendicular plane, a face-back direction, a toe-heel direction, and an up-down direction are defined as follows. The 45 reference state is defined as a state where a head is placed at a predetermined lie angle and real loft angle on a horizontal plane HP. As shown in FIG. 21, in the reference state, a center line Z of a hosel hole is contained in a plane VP that is perpendicular to the horizontal plane HP. The plane VP is defined as the reference perpendicular plane. The predetermined lie angle and real loft angle are shown in a product catalog, for example.

In the present disclosure, the toe-heel direction is the 50 direction of an intersection line NL between the reference perpendicular plane VP and the horizontal plane HP (see FIG. 21).

In the present disclosure, the face-back direction is a direction that is perpendicular to the toe-heel direction and is parallel to the horizontal plane HP.

In the present disclosure, the up-down direction is a 55 direction that is perpendicular to the toe-heel direction and is perpendicular to the face-back direction. In other words, the up-down direction in the present disclosure is a direction perpendicular to the horizontal plane HP.

60 In the present disclosure, a face center Fc is defined. The face center Fc is determined in the following manner. First, a point Pr is selected roughly at the center of a face outer

surface in the up-down direction and the toe-heel direction. Next, a plane that passes through the point P_r , extends in the direction of a line normal to the face outer surface at the point P_r , and is parallel to the toe-heel direction is determined. An intersection line between this plane and the face outer surface is drawn, and a midpoint P_x of this intersection line is determined. Next, a plane that passes through the midpoint P_x , extends in the direction of a line normal to the face outer surface at the midpoint P_x , and is parallel to the up-down direction is determined. An intersection line between this plane and the face outer surface is drawn, and a midpoint P_y of this intersection line is determined. Next, a plane that passes through the midpoint P_y , extends in the direction of a line normal to the face outer surface at the midpoint P_y , and is parallel to the toe-heel direction is determined. An intersection line between this plane and the face outer surface is drawn, and a midpoint P_x of this intersection line is newly determined. Next, a plane that passes through this newly-determined midpoint P_x , extends in the direction of a line normal to the face outer surface at this midpoint P_x , and is parallel to the up-down direction is determined. An intersection line between this plane and the face outer surface is drawn, and a midpoint P_y of this intersection line is newly determined. By repeating the above-described steps, points P_x and P_y are sequentially determined. In the course of repeating these steps, when the distance between a newly-determined midpoint P_y and a midpoint P_y determined in the immediately preceding step first becomes less than or equal to 0.5 mm, the newly-determined midpoint P_y (the midpoint P_y determined last) is defined as the face center F_c .

FIG. 1 is a plan view of a golf club head 2 according to a first embodiment as viewed from a crown side. FIG. 2A is a bottom view of the head 2 as viewed from a sole side. FIG. 3A is a cross-sectional view taken along line A-A in FIG. 2. FIG. 3B is a cross-sectional view taken along line B-B in FIG. 2. FIG. 3C is a cross-sectional view taken along lines C-C in FIG. 3A and FIG. 3B.

The head 2 (head body $h1$) includes a face portion 4, a crown portion 6, a sole portion 8, and a hosel portion 10. The face portion 4 includes a face outer surface 4a and a face inner surface 4b (not shown in the drawings). The face outer surface 4a is a surface for hitting a ball. The face outer surface 4a has a face center F_c . The crown portion 6 includes a crown outer surface 6a and a crown inner surface (not shown in the drawings). The sole portion 8 includes a sole outer surface 8a and a sole inner surface 8b (see FIG. 3A). The hosel portion 10 has a hosel hole 12. The head 2 is a wood-type golf club head.

The head 2 includes a first wound portion b1, a second wound portion b2, and a weight member wt. The first wound portion b1 and the second wound portion b2 are attached to the head body $h1$, and the weight member wt is stretched between the first wound portion b1 and the second wound portion b2. In the present embodiment, the sole portion 8 includes the first wound portion b1 and the second wound portion b2. The first wound portion b1 and the second wound portion b2 are connected to each other by the weight member wt. The first wound portion b1 is provided at a toe-side position with respect to the second wound portion b2. The first wound portion b1 is provided at a toe-side position with respect to the face center F_c . The second wound portion b2 is provided at a heel-side position with respect to the face center F_c .

The weight member wt has a long and thin shape. The length of the weight member wt is set such that the weight member wt can connect the first wound portion b1 and the

second wound portion b2, and have a first part wt1 to be wound around the first wound portion b1 or a second part wt2 to be wound around the second wound portion b2. Examples of the shape of the weight member wt include a wire shape and a belt shape. Examples of the wire-shaped weight member wt include a string, a piece of wire, a metal wire, and wire. The wire is a concept that includes a piece of wire and a wire rope obtained by twisting wires together. The weight member wt may be a chain, for example. The material of the weight member wt is not limited. The weight member wt preferably has a large specific gravity. From the viewpoint of specific gravity and easy winding, a resin containing metal and metal powder is preferable as the material of the weight member wt. Specific examples of the material of the weight member wt include stainless steel, a tungsten nickel alloy, a resin material containing stainless steel, and a resin material containing a tungsten nickel alloy.

In a single weight member wt, its weight per unit length may be constant or may vary.

As shown in FIG. 3A, the first wound portion b1 includes a reel portion 20 and a center shaft 22. The reel portion 20 constitutes a reel (spool). The reel portion 20 is fixed to the center shaft 22. The reel portion 20 can rotate about the center shaft 22. The weight member wt is wound around the first wound portion b1 (reel portion 20). Of the weight member wt, a portion that is wound around the first wound portion b1 is referred to as the first part wt1. The length (length in the longitudinal direction) of the first part wt1 varies depending on how much the weight member wt is wound around the first wound portion b1. The weight of the first part wt1 varies depending on how much the weight member wt is wound around the first wound portion b1.

The first wound portion b1 has an engaging hole 24. The engaging hole 24 is shaped so as to engage with the tip portion of a tool that is used to rotate the first wound portion b1. The tool is a screw driver, for example. The first wound portion b1 can be rotated by this tool.

The first wound portion b1 can rotate in a reel-in direction and a reel-out direction. When the first wound portion b1 rotates in the reel-in direction, the weight member wt is wound around the first wound portion b1, and the length of the first part wt1 increases. When the first wound portion b1 rotates in the reel-out direction, the weight member wt is unwound from the first wound portion b1, and the length of the first part wt1 decreases.

The configuration of the second wound portion b2 is the same as that of the first wound portion b1. As shown in FIG. 3B, the second wound portion b2 includes a reel portion 20 and a center shaft 22. The reel portion 20 constitutes a reel (spool). The reel portion 20 is fixed to the center shaft 22. The weight member wt is wound around the second wound portion b2 (reel portion 20). Of the weight member wt, a portion that is wound around the second wound portion b2 is referred to as the second part wt2. The length (length in the longitudinal direction) of the second part wt2 varies depending on how much the weight member wt is wound around the second wound portion b2. The weight of the second part wt2 varies depending on how much the weight member wt is wound around the second wound portion b2.

The second wound portion b2 can rotate in the reel-in direction and the reel-out direction. When the second wound portion b2 rotates in the reel-in direction, the weight member wt is wound around the second wound portion b2, and the length of the second part wt2 increases. When the second wound portion b2 rotates in the reel-out direction, the weight

member **wt** is unwound from the second wound portion **b2**, and the length of the second part **wt2** decreases.

The rotation of the first wound portion **b1** and the rotation of the second wound portion **b2** can be linked together by the weight member **wt**. When a rotation force is applied to the first wound portion **b1** to rotate the first wound portion **b1** in the reel-in direction, this rotation can involve the rotation of the second wound portion **b2** in the reel-out direction. When a rotation force is applied to the second wound portion **b2** to rotate the second wound portion **b2** in the reel-in direction, this rotation can involve the rotation of the first wound portion **b1** in the reel-out direction. This linkage provides easier adjustability of the position of the center of gravity of the head.

The weight member **wt** includes a third part **wt3**. The third part **wt3** is a portion that is not wound around any wound portion **b1** or **b2**. In the present embodiment, the third part **wt3** is a part located between the first part **wt1** and the second part **wt2**.

When the third part **wt3** is pulled by the first wound portion **b1** and the second wound portion **b2**, a tension can be applied to the third part **wt3**. When the tension is applied to the third part **wt3**, the length of the third part **wt3** is substantially constant. When the tension is not applied to the third part **wt3**, the third part **wt3** might go slack.

The second wound portion **b2** has an engaging hole **24**. The engaging hole **24** is shaped so as to engage with the tip portion of a tool that is used to rotate the second wound portion **b2**. The tool is a screw driver, for example. This tool can be also used as the tool for rotating the first wound portion **b1**.

As shown in FIG. 3C, the first wound portion **b1** includes a rotation resistance mechanism **30**. The rotation resistance mechanism **30** includes a rotary gear **32** and a gear engaging portion **34**. The rotary gear **32** is fixed to the center shaft **22** and rotates together with the reel portion **20**. The gear engaging portion **34** engages with teeth **32a** of the rotary gear **32**. This engagement prevents the rotation of the rotary gear **32**. When the rotary gear **32** is about to rotate, the rotary gear **32** applies a stress on the gear engaging portion **34**. The gear engaging portion **34** is elastically deformed by the stress applied from the rotary gear **32**. When the magnitude of the stress from the rotary gear **32** exceeds a predetermined value, the degree of the elastic deformation of the gear engaging portion **34** increases, and the gear engaging portion **34** gets over one of the teeth **32a**. By repeating the elastic deformation, the rotary gear **32** rotates while receiving the rotational resistance. The rotation resistance mechanism **30** applies a same magnitude of resistance force to the rotation of the rotary gear **32** in the reel-in direction and the rotation of the rotary gear **32** in the reel-out direction.

The second wound portion **b2** also includes the same rotation resistance mechanism **30** as in the first wound portion **b1**.

When the first wound portion **b1** is rotated in the reel-in direction, the weight of the first part **wt1** increases and the weight of the second part **wt2** decreases. That is, the weight of the weight member **wt** is distributed largely to the first part **wt1**. As a result, the position of the center of gravity of the head **2** is shifted toward the first wound portion **b1**. In the present embodiment, the position of the center of gravity of the head **2** is shifted toward the toe side.

When the second wound portion **b2** is rotated in the reel-in direction, the weight of the second part **wt2** increases and the weight of the first part **wt1** decreases. That is, the weight of the weight member **wt** is distributed largely to the second part **wt2**. As a result, the position of the center of

gravity of the head **2** is shifted toward the second wound portion **b2**. In the present embodiment, the position of the center of gravity of the head **2** is shifted to the heel side.

The rotation resistance mechanism **30** contributes to keeping the tension applied to the third part **wt3**.

The head **2** includes a first port **p1** and a second port **p2**. The head body **h1** of the head **2** includes the first port **p1** and the second port **p2**. In the present embodiment, the first port **p1** and the second port **p2** are provided in the sole portion **8**.

10 As shown in FIG. 3A, the first port **p1** houses the first wound portion **b1**. The first wound portion **b1** does not protrude further outward of the head **2** than the sole outer surface **8a**. As shown in FIG. 3B, the second port **p2** houses the second wound portion **b2**. The second wound portion **b2** does not protrude further outward of the head **2** than the sole outer surface **8a**.

15 The head **2** has a housing recess **p3**. The housing recess **p3** extends from the first port **p1** to the second port **p2**. The housing recess **p3** constitutes a groove. The housing recess

20 **p3** houses the third part **wt3**. As long as the tension is applied to the third part **wt3**, the third part **wt3** is housed in the housing recess **p3**. Since the third part **wt3** is housed in the housing recess **p3**, the third part **wt3** is disposed inside the sole outer surface **8a**.

25 FIG. 4A is an enlarged cross-sectional view showing a first wound portion **b1** and its vicinity according to a first modification example, and FIG. 4B is an enlarged cross-sectional view showing a second wound portion **b2** and its vicinity according to the first modification example. FIG. 4C

30 is a cross-sectional view taken along lines C-C in FIG. 4A and FIG. 4B. A head of the first modification example is the same as the head **2** of the first embodiment except for structures described below.

35 In the first modification example, a ratchet mechanism **40** is provided instead of the rotation resistance mechanism **30**. The first wound portion **b1** and the second wound portion **b2** each have the ratchet mechanism **40**.

The ratchet mechanism **40** includes a rotary gear **42** and a gear engaging portion **44**. The rotary gear **42** rotates 40 together with the reel portion **20**. The gear engaging portion **44** constitutes a switching cam. The gear engaging portion **44** includes a first engaging portion **44a** and a second engaging portion **44b**. The gear engaging portion **44** is structured such that mutual transition (switching) between a 45 first state in which the first engaging portion **44a** engages with the rotary gear **42** and a second state in which the second engaging portion **44b** engages with the rotary gear **42** can be performed. That is, the gear engaging portion **44** can switch between the first state and the second state. FIG. 4C shows the first state. The first state allows the rotary gear **42** 50 to rotate in a first direction **R1**, and prevents the rotary gear **42** from rotating in a second direction **R2**. The second state allows the rotary gear **42** to rotate in the second direction **R2**, and prevents the rotary gear **42** from rotating in the first direction **R1**. The first direction **R1** is the reel-in direction, and the second direction **R2** is the reel-out direction. This ratchet mechanism can change the rotation direction between the reel-in direction and the reel-out direction. The ratchet mechanism is used, for example, in a ratchet handle 55 for fastening a nut and a bolt.

For rotating the first wound portion **b1** in the reel-in direction, the first wound portion **b1** is set to the first state, the second wound portion **b2** is set to the second state, and then the first wound portion **b1** is rotated in the reel-in direction. For rotating the second wound portion **b2** in the reel-in direction, the second wound portion **b2** is set to the first state, the first wound portion **b1** is set to the second

state, and then the second wound portion b2 is rotated in the reel-in direction. The slack of the third part wt3 can be taken up by setting both the first wound portion b1 and the second wound portion b2 to the first state, and rotating the first wound portion b1 or the second wound portion b2 in the reel-in direction.

FIG. 5A and FIG. 5B are enlarged cross-sectional views each showing a first wound portion b1 and its vicinity according to a second modification example. In FIG. 5A, the first wound portion b1 is situated at a pushed-in position. At the pushed-in position, the first wound portion b1 is housed in a first port p1. FIG. 5A also shows a cross-sectional view taken along line A-A. In FIG. 5B, the first wound portion b1 is situated at a projecting position. FIG. 5B also shows a cross-sectional view taken along line B-B.

In this second modification example, the configuration of the second wound portion b2 is the same as that of the first wound portion b1. FIG. 5A and FIG. 5B also show enlarged sectional views of the second wound portion b2 and its vicinity in the second modification example.

In the second modification example, a rotation prevention mechanism 50 and an alternate mechanism 60 are provided instead of the rotation resistance mechanism 30. In addition, in this modification example, a reel portion 70 is provided instead of the reel portion 20. The first wound portion b1 includes the rotation prevention mechanism 50, the alternate mechanism 60, and the reel portion 70. The second wound portion b2 includes the rotation prevention mechanism 50, the alternate mechanism 60, and the reel portion 70. The head of the second modification example is the same as the head 2 of the first embodiment except for structures described below.

The reel portion 70 is not fixed to a rotation supporting shaft 72. The reel portion 70 is rotatably supported by the rotation supporting shaft 72. The reel portion 70 can rotate with respect to the rotation supporting shaft 72. The reel portion 70 is fixed to the rotation supporting shaft 72 through a bearing 74.

The rotation prevention mechanism 50 includes a rotary gear 52 and a gear engaging portion 54. The gear engaging portion 54 constitutes a rotation preventing portion that engages with teeth 52a of the rotary gear 52 to prevent the rotation of the rotary gear 52. The rotary gear 52 is provided in the reel portion 70.

As shown in FIG. 5A, when the first wound portion b1 is situated at the pushed-in position, the rotary gear 52 engages with the gear engaging portion 54, which prevents the rotation of the first wound portion b1. As shown in FIG. 5B, when the first wound portion b1 is situated at the projecting position, the rotary gear 52 does not engage with the gear engaging portion 54, which allows the rotation of the first wound portion b1.

When the first wound portion b1 situated at the pushed-in position is pushed, the first wound portion b1 is shifted to the projecting position, and the first wound portion b1 stays at the projecting position even after stopping pushing the first wound portion b1. When the first wound portion b1 situated at the projecting position is pushed, the first wound portion b1 is shifted to the pushed-in position, and the first wound portion b1 stays at the pushed-in position even after stopping pushing the first wound portion b1. Such an action (motion) of the first wound portion b1 is also referred to as an alternate action. The alternate mechanism 60 enables the first wound portion b1 to perform the alternate action. The alternate mechanism 60 is configured such that a mutual transition (switching) between the pushed-in position and the projecting position can be performed. The first wound

portion b1 situated at the pushed-in position does not protrude further outward than the sole outer surface 8a. The first wound portion b1 situated at the projecting position protrudes further outward than the sole outer surface 8a.

The pushing of the first wound portion b1 can be achieved by pushing the first wound portion b1 with a finger, for example. The mutual transition of the first wound portion b1 between the pushed-in position and the projecting position can be achieved by simply pushing the first wound portion b1 with a finger. Every time the first wound portion b1 is pushed, the switching of the first wound portion b1 between the pushed-in position and the projecting position is performed.

FIG. 6 shows a cross-sectional view of the alternate mechanism 60. An upper part in FIG. 6 shows a cross-sectional view when the first wound portion b1 (second wound portion b2) is situated at the pushed-in position. A lower part in FIG. 6 is a cross-sectional view when the first wound portion b1 (second wound portion b2) is situated at the projecting position.

The alternate mechanism 60 includes a heart-shaped cam 62, a pin 64, a biasing member 66, and a moving portion 68. The cam 62 is fixed to the moving portion 68. The pin 64 is made of a metal and a rod-shaped member.

The pin 64 is fixed in a cantilever state in which an end portion (lower end portion in FIG. 6) of the pin 64 on a farther side from the cam 62 is supported. An end portion 64a (upper end portion in FIG. 6) of the pin 64 on a closer side to the cam 62 is a free end. The free end 64a is provided with an engaging portion 64b that engages with the cam 62. A drawing within a circle in FIG. 6 shows the free end 64a as viewed from another angle, and also shows the engaging portion 64b. An angled end portion 64a of the pin 64 forms the engaging portion 64b. When a main portion 64c of the pin 64 is bent by an external force, the main portion 64c of the pin 64 tends to return to a natural state (a straightly extending state).

The biasing member 66 is a compression coil spring. The biasing member 66 biases the moving portion 68 upward at all times. The biasing member 66 biases the moving portion 68 at all times in a direction in which the cam 62 moves away from the pin 64.

The rotation supporting shaft 72 is fixed to the moving portion 68. The first wound portion b1 moves in conjunction with the movement of the moving portion 68. The first wound portion b1 moves together with the moving portion 68.

The cam 62 includes a first guide surface 62a, a recess 62b, and a second guide surface 62c. A pin guiding portion 63 is provided in the vicinity of the cam 62.

When the pin 64 engages with the cam 62, the first wound portion b1 stays at the pushed-in position while resisting the biasing force of the biasing member 66 (see upper part of FIG. 6). When the engagement between the pin 64 and the cam 62 is released, the first wound portion b1 is shifted to the projecting position because of the biasing force of the biasing member 66 (see lower part of FIG. 6).

When the first wound portion b1 situated at the projecting position is pushed, the cam 62 located apart from the pin 64 comes closer to the pin 64. The engaging portion 64b of the pin 64 abuts on the first guide surface 62a of the cam 62, is guided by the first guide surface 62a, and is also guided by the pin guiding portion 63 to reach the recess 62b. The engaging portion 64b engages with the recess 62b, whereby the first wound portion b1 is shifted to and kept at the pushed-in position (see upper part of FIG. 6).

When the first wound portion **b1** situated at the pushed-in position is pushed, the engaging portion **64b** comes off the recess **62b** since the pin **64** tends to return to its natural state from elastically deformed state, moves along the second guide surface **62c**, and moves away from the cam **62**. As a result, the first wound portion **b1** returns to the projecting position.

As described above, in the present embodiment, the heart-shaped cam mechanism is adopted as the alternate mechanism **60**. Examples of the alternate mechanism **60** include known mechanisms such as a rotary cam mechanism and a ratchet cam mechanism in addition to a heart-shaped cam mechanism.

FIG. 7 is a bottom view of a head **100** according to a second embodiment as viewed from the sole side. In the head **100**, each reel portion **20** of a first wound portion **b1** and a second wound portion **b2** has transparency. In the head **100**, a first part **wt1** that is wound around the first wound portion **b1** is visually recognized from the outside of the head **100**. In the head **100**, a second part **wt2** that is wound around the second wound portion **b2** can be visually recognized from the outside of the head **100**. Except for the above-described structures, the head **100** is the same as the head **2**. The head **100** does not have a first wound portion **b1** or a second wound portion **b2** in the crown portion.

FIG. 8 is a bottom view of a head **110** according to a third embodiment as viewed from the sole side. In the head **110**, a notch **20a** is provided in each reel portion **20** of a first wound portion **b1** and a second wound portion **b2**. A first part **wt1** that is wound around the first wound portion **b1** is visually recognized from the outside of the head **110** through the notch **20a**. A second part **wt2** that is wound around the second wound portion **b2** can be visually recognized from the outside of the head **110** through the notch **20a**. Except for the above-described structures, the head **110** is the same as the head **2**. The head **110** does not have a first wound portion **b1** or a second wound portion **b2** in the crown portion.

FIG. 9 is a bottom view of a head **120** according to a fourth embodiment as viewed from the sole side. The head **120** (sole portion **8**) includes a first wound portion **b1**, a first port **p1** that houses the first wound portion **b1**, a second wound portion **b2**, and a second port **p2** that houses the second wound portion **b2**. The head **120** (sole portion **8**) further includes a projection **t1** and a projection **t2**. The projection **t1** and the projection **t2** are disposed on the heel side with respect to the first wound portion **b1**. The projection **t1** and the projection **t2** are disposed on the toe side with respect to the second wound portion **b2**. The projection **t1** and the projection **t2** are erected columns. The number of the projections may be one, but is preferably two or more.

A weight member **wt** can be wound around the projection **t1**. The weight member **wt** can be wound around the projection **t2**. Each of the projection **t1** and the projection **t2** is relatively thin. Accordingly, when the weight member **wt** is wound around each of the projection **t1** and the projection **t2**, the length of a portion wound around the projection(s) is not efficiently increased. As shown in FIG. 9, in the present embodiment, the weight member **wt** is wound around the projection **t1** and the projection **t2** so as to be stretched from the projection **t1** to the projection **t2**. By winding the weight member **wt** in this manner, the length of a part (hereinafter referred to as a projection wound portion **wt31**) of the weight member **wt** that is wound around the projection **t1** and the projection **t2** can be increased. The weight member **wt** can be wound in various forms.

In the head **120** (the sole portion **8**), the weight member **wt** includes a first part (not shown) that is wound around the

first wound portion **b1**, a second part (not shown) that is wound around the second wound portion **b2**, and a third part **wt3** that is a portion other than the first part or the second part. The third part **wt3** includes the projection wound portion **wt31** wound around the projections **t1** and **t2**, an extension portion **wt32** that extends from the projection wound portion **wt31** to the first wound portion **b1** (first part **wt1**), and an extension portion **wt33** that extends from the projection wound portion **wt31** to the second wound portion **b2** (second part **wt2**).

A housing recess **p3** houses (the entirety of) the third part **wt3**. The housing recess **p3** includes a first recess **p31** that houses the projection **t1**, the projection **t2** and the projection wound portion **wt31**, a second recess **p32** that houses the extension portion **wt32**, and a third recess **p33** that houses the extension portion **wt33**. Neither the projection **t1** nor the projection **t2** protrudes further outward than the sole outer surface **8a**. The third part **wt3** does not protrude further outward than the sole outer surface **8a**.

Except for the above-described structures, the head **120** is the same as the head **2**. The head **120** does not have a first wound portion **b1** or a second wound portion **b2** in the crown portion.

FIG. 10 is a bottom view of a head **130** according to a fifth embodiment as viewed from the sole side. The head **130** (sole portion **8**) includes a first wound portion **b1**, a first port **p1** that houses the first wound portion **b1**, a second wound portion **b2**, and a second port **p2** that houses the second wound portion **b2**. The head **130** (sole portion **8**) further includes a projection **t1**, a projection **t2**, a projection **t3**, and a projection **t4**. The projection **t1** and the projection **t2** are disposed on the toe side with respect to the projection **t3** and the projection **t4**. The projection **t1** and the projection **t2** are disposed on the face side of the first wound portion **b1**. The projection **t3** and the projection **t4** are disposed on the face side of the second wound portion **b2**.

In the head **130** (sole portion **8**), the weight member **wt** includes a first part (not shown) that is wound around the first wound portion **b1**, a second part (not shown) that is wound around the second wound portion **b2**, and a third part **wt3** that is a portion other than the first part or the second part. The third part **wt3** includes a projection wound portion **wt31** that is wound around the projections **t1** and **t2**, a projection wound portion **wt32** that is wound around the projections **t3** and **t4**, and an extension portion **wt33** that extends from the first wound portion **b1** (first part **wt1**) to the second wound portion **b2** (second part **wt2**). The third part **wt3** further includes an extension portion **wt34** that extends from the projections **t1** and **t2** to the first wound portion **b1**, and an extension portion **wt35** that extends from the projections **t3** and **t4** to the second wound portion **b2**.

A housing recess **p3** houses (the entirety of) the third part **wt3**. The housing recess **p3** includes: a first recess **p31** that houses the projection **t1**, the projection **t2** and the projection wound portion **wt31**; a second recess **p32** that houses the projection **t3**, the projection **t4**, and the projection wound portion **wt32**; and a third recess **p33** that houses the extension portion **wt33**. The housing recess **p3** further includes a fourth recess **p34** that houses the extension portion **wt34**, and a fifth recess **p35** that houses the extension portion **wt35**.

Neither the projection **t1** nor the projection **t2** protrudes further outward than the sole outer surface **8a**. Neither the projection **t3** nor the projection **t4** protrudes further outward than the sole outer surface **8a**. The third part **wt3** does not protrude further outward than the sole outer surface **8a**.

11

Except for the above-described structures, the head **130** is the same as the head **2**. The head **130** does not have a first wound portion **b1** or a second wound portion **b2** in the crown portion.

FIG. 11 is a bottom view of a head **140** according to a sixth embodiment as viewed from the sole side. The head **140** (sole portion **8**) includes a first wound portion **b1** and a second wound portion **b2**. The head **140** (sole portion **8**) does not have a first port **p1**. The first wound portion **b1** is exposed to the outside of the sole outer surface **8a**. The head **140** (sole portion **8**) does not have a second port **p2**. The second wound portion **b2** is exposed to the outside of the sole outer surface **8a**.

The head **140** (sole portion **8**) includes a projection **t1**, a projection **t2**, a projection **t3**, and a projection **t4**. The projection **t1**, the projection **t2**, the projection **t3**, and the projection **t4** are disposed on the heel side with respect to the first wound portion **b1**. The projection **t1**, the projection **t2**, the projection **t3**, and the projection **t4** are disposed on the toe side with respect to the second wound portion **b2**.

The head **140** (sole portion **8**) does not have a housing recess **p3** that houses a third part **wt3**. The third part **wt3** protrudes further outward than the sole outer surface **8a**. The projection **t1**, the projection **t2**, the projection **t3**, and the projection **t4** protrude further outward than the sole outer surface **8a**.

The third part **wt3** can be wound around at least one of the projection **t1**, the projection **t2**, the projection **t3**, or the projection **t4** at a position located between the first wound portion **b1** (first part **wt1**) and the second wound portion **b2** (second part **wt2**). The third part **wt3** may be wound so as to be stretched between two or more projections selected from the group consisting of the projection **t1**, the projection **t2**, the projection **t3**, and the projection **t4**. The third part **wt3** can be wound in various forms using the plurality of projections.

Except for the above-described structures, the head **140** is the same as the head **2**. The head **140** does not have a first wound portion **b1** or a second wound portion **b2** in the crown portion.

FIG. 12 is a bottom view of a head **150** according to a seventh embodiment as viewed from the sole side. The head **150** (sole portion **8**) includes a first wound portion **b1** and a second wound portion **b2**. The head **150** (sole portion **8**) does not have a first port **p1**. The first wound portion **b1** is exposed to the outside of the sole outer surface **8a**. The head **150** (sole portion **8**) does not have the second port **p2**. The second wound portion **b2** is exposed to the outside of the sole outer surface **8a**. The head **150** (sole portion **8**) does not have a housing recess **p3**. A weight member **wt** (third part **wt3**) that extends from the first wound portion **b1** to the second wound portion **b2** protrudes further outward than the sole outer surface **8a**. The head **150** (sole portion **8**) does not have a projection around which the weight member **wt** can be wound. Neither the first wound portion **b1** nor the second wound portion **b2** includes the engaging hole **24**. The first wound portion **b1** and the second wound portion **b2** are non-rotatable. For example, the weight member **wt** can be wound around the first wound portion **b1** and the second wound portion **b2** with fingers.

FIG. 13A is a plan view of a head **160** according to an eighth embodiment as viewed from the crown side. FIG. 13B is a bottom view of the head **160** as viewed from the sole side. In the head **160**, a crown portion **6** includes a first wound portion **b1** and a second wound portion **b2**. The crown portion **6** further includes a first port **p1** that houses the first wound portion **b1**, a second port **p2** that houses the second wound portion **b2**, and a housing recess **p3** that extends from the first port **p1** to the second port **p2** and houses a third part **wt3** of a weight member **wt**.

second wound portion **b2**, and a housing recess **p3** that extends from the first port **p1** to the second port **p2** and houses a third part **wt3** of a weight member **wt**. A sole portion **8** does not have a first wound portion **b1** or a second wound portion **b2**. Except for the above-described structures, the head **160** is the same as the head **2**.

FIG. 14 is a plan view of a head **170** according to a ninth embodiment as viewed from the crown side. A cover member **172** that covers the first port **p1**, the second port **p2**, and the housing recess **p3** is attached to the head **170**. The cover member **172** is attached to the head **170** by a known method such as fitting or screwing. The cover member **172** may cover at least a part of the first port **p1**, the second port **p2**, or the housing recess **p3**. For example, a first cover member that covers the first port **p1** and a second cover member that covers the second port **p2** may be provided. The head **170** is the same as the head **160** except for the presence of the cover member **172**.

FIG. 15A is a plan view of a head **180** according to a tenth embodiment as viewed from the crown side. FIG. 15B is a bottom view of the head **180** as viewed from the sole side. In the head **180**, a crown portion **6** includes a first wound portion **b1** and a second wound portion **b2**. The crown portion **6** further includes a first port **p1** that houses the first wound portion **b1**, a second port **p2** that houses the second wound portion **b2**, and a housing recess **p3** that extends from the first port **p1** to the second port **p2** and houses a third part **wt3** of a weight member **wt**. In addition, a sole portion **8** of the head **180** includes a first wound portion **b1** and a second wound portion **b2**. The sole portion **8** further includes a first port **p1** that houses the first wound portion **b1**, a second port **p2** that houses the second wound portion **b2**, and a housing recess **p3** that extends from the first port **p1** to the second port **p2** and houses a third part **wt3** of a weight member **wt**.

FIG. 16A is a plan view of a head **190** according to an eleventh embodiment as viewed from the crown side. FIG. 16B is a bottom view of the head **190** as viewed from the sole side. In the head **190**, a crown portion **6** includes a first wound portion **b1**, and a sole portion **8** includes a second wound portion **b2**. The crown portion **6** includes a first port **p1** that houses the first wound portion **b1**. The sole portion **8** includes a second port **p2** that houses the second wound portion **b2**. A housing recess **p3** extends from the crown portion **6** to the sole portion **8**. The housing recess **p3** extends from the first port **p1** located in the crown portion **6** to the second port **p2** located in the sole portion **8**. The housing recess **p3** is a groove that houses a third part **wt3** of a weight member **wt**.

FIG. 17 is a bottom view of a golf club head **200** according to a twelfth embodiment as viewed from the sole side. FIG. 18A is a cross-sectional view taken along line A-A in FIG. 17. FIG. 18B is a cross-sectional view taken along line B-B in FIG. 17. FIG. 18C is a cross-sectional view taken along lines C-C in FIG. 18A and FIG. 18B.

The head **200** (head body **h1**) includes a face portion **4**, a crown portion **6**, a sole portion **8**, and a hosel portion **10**. The plan view of the head **200** as viewed from the crown side is the same as FIG. 1. The sole portion **8** includes a sole outer surface **8a** and a sole inner surface **8b** (see FIG. 18A and FIG. 18B).

The head **200** includes a first wound portion **b1**, a second wound portion **b2**, and a weight member **wt**. The first wound portion **b1** and the second wound portion **b2** are attached to the head body **h1**, and the weight member **wt** is stretched between the first wound portion **b1** and the second wound portion **b2**. In the present embodiment, the sole portion **8** includes the first wound portion **b1** and the second wound

portion b2. The first wound portion b1 and the second wound portion b2 are connected to each other by the weight member wt. The first wound portion b1 is provided on the toe side with respect to the second wound portion b2. The first wound portion b1 is provided on the toe side with respect to the face center Fc. The second wound portion b2 is provided on the heel side with respect to the face center Fc.

The weight member wt has a long and thin shape. The length of the weight member wt is set such that the weight member wt can connect the first wound portion b1 and the second wound portion b2, and have a first part wt1 to be wound around the first wound portion b1 or a second part wt2 to be wound around the second wound portion b2.

As shown in FIG. 18A, the first wound portion b1 includes a reel portion 20 and a screw 23. The reel portion 20 constitutes a reel (spool). The screw 23 penetrates through a through hole 20b that is formed at the center of the reel portion 20. Further, the screw 23 is screwed into a female screw hole 25 that is formed in a bottom portion p11 of a first port p1. The reel portion 20 can freely rotate with respect to the screw 23.

The weight member wt is wound around the first wound portion b1 (reel portion 20). Of the weight member wt, a portion that is wound around the first wound portion b1 is referred to as the first part wt1. The length (length in the longitudinal direction) of the first part wt1 varies depending on how much the weight member wt is wound around the first wound portion b1. The weight of the first part wt1 varies depending on how much the weight member wt is wound around the first wound portion b1.

The first wound portion b1 has an engaging hole 24. The engaging hole 24 is shaped so as to engage with the tip portion of a tool that is used to rotate the first wound portion b1. The tool is a screw driver, for example. The first wound portion b1 can be rotated by this tool.

The screw 23 includes a head portion that has a screw hole 27. The screw hole 27 is shaped so as to engage with the tip portion of a tool that is used to rotate the screw 23. The tool is a screw driver, for example. The screw 23 can be tightened or loosened with this tool.

The configuration of the second wound portion b2 is the same as that of the first wound portion b1. As shown in FIG. 18B, the second wound portion b2 includes a reel portion 20 and a screw 23. The reel portion 20 constitutes a reel (spool). The reel portion 20 can freely rotate with respect to the screw 23. The reel portion 20 can rotate about the screw 23. The weight member wt is wound around the second wound portion b2 (reel portion 20). Of the weight member wt, a portion that is wound around the second wound portion b2 is referred to as the second part wt2. The length (length in the longitudinal direction) of the second part wt2 varies depending on how much the weight member wt is wound around the second wound portion b2. The weight of the second part wt2 varies depending on how much the weight member wt is wound around the second wound portion b2.

The rotation of the first wound portion b1 and the rotation of the second wound portion b2 can be linked together by the weight member wt. When a rotation force is applied to the first wound portion b1 to rotate the first wound portion b1 in the reel-in direction, this rotation can involve the rotation of the second wound portion b2 in the reel-out direction. When a rotation force is applied to the second wound portion b2 to rotate the second wound portion b2 in the reel-in direction, this rotation can involve the rotation of the first wound

portion b1 in the reel-out direction. This linkage provides easier adjustability of the position of the center of gravity of the head.

The weight member wt includes a third part wt3. The third part wt3 is a portion that is not wound around any wound portion b1 or b2. In the present embodiment, the third part wt3 is a part located between the first part wt1 and the second part wt2.

The second wound portion b2 has an engaging hole 24. 10 The engaging hole 24 is shaped so as to engage with the tip portion of a tool that is used to rotate the second wound portion b2. The tool is a screw driver, for example. This tool is also used as the tool for rotating the first wound portion b1.

As shown in FIG. 18C, the first wound portion b1 includes a rotation resistance mechanism 30. The rotation resistance mechanism 30 includes a rotary gear 32 and a gear engaging portion 34. The rotary gear 32 is integrally formed with the reel portion 20 as a single-piece member. The rotary gear 32 rotates together with the reel portion 20. The gear engaging portion 34 engages with teeth 32a of the rotary gear 32. This engagement prevents the rotation of the rotary gear 32. When the rotary gear 32 is about to rotate, the rotary gear 32 25 applies a stress on the gear engaging portion 34. The gear engaging portion 34 is elastically deformed by the stress applied from the rotary gear 32. When the magnitude of the stress from the rotary gear 32 exceeds a predetermined value, the degree of the elastic deformation of the gear engaging portion 34 increases, and the gear engaging portion 34 gets over one of the teeth 32a. By repeating the elastic deformation, the rotary gear 32 rotates while receiving the rotational resistance. The rotation resistance mechanism 30 applies a same magnitude of resistance force to the 30 rotation of the rotary gear 32 in the reel-in direction and the rotation of the rotary gear 32 in the reel-out direction.

The second wound portion b2 also includes the same rotation resistance mechanism 30 as in the first wound portion b1.

40 When the first wound portion b1 is rotated in the reel-in direction, the weight of the first part wt1 increases and the weight of the second part wt2 decreases. That is, the weight of the weight member wt is distributed largely to the first part wt1. As a result, the position of the center of gravity of the head 200 is shifted toward the first wound portion b1. In the present embodiment, the position of the center of gravity of the head 200 is shifted toward the toe side.

When the second wound portion b2 is rotated in the reel-in direction, the weight of the second part wt2 increases and the weight of the first part wt1 decreases. That is, the weight of the weight member wt is distributed largely to the second part wt2. As a result, the position of the center of gravity of the head 200 is shifted toward the second wound portion b2. In the present embodiment, the position of the center of gravity of the head 200 is shifted to the heel side.

55 The rotation resistance mechanism 30 contributes to keeping the tension applied to the third part wt3.

FIG. 18A shows a state in which the screw 23 is tightened and a state in which the screw 23 is loosened. A left-side part 60 of FIG. 18A shows the state in which the screw 23 is tightened. A right-side part of FIG. 18A shows the state in which the screw 23 is loosened.

Similarly, FIG. 18B shows a state in which the screw 23 is tightened and a state in which the screw 23 is loosened. A left-side part of FIG. 18B shows the state in which the screw 23 is tightened. A right-side part of FIG. 18B shows the state in which the screw 23 is loosened.

15

As shown in FIG. 18A, the rotary gear 32 is pressed against the bottom portion p11 of the first port p1 by tightening the screw 23. The rotation of the first wound portion b1 (reel portion 20) can be stopped by tightening the screw 23. Slack of the third part wt3 can be prevented by preventing the rotation of the first wound portion b1. Loosening the screw 23 allows the first wound portion b1 to rotate.

As shown in FIG. 18B, the rotary gear 32 is pressed against a bottom portion p21 of a second port p2 by tightening the screw 23. The rotation of the second wound portion b2 (reel portion 20) can be stopped by tightening the screw 23. Slack of the third part wt3 can be prevented by preventing the rotation of the second wound portion b2. Loosening the screw 23 allows the second wound portion b2 to rotate.

As described above, the present embodiment includes a rotation stop mechanisms that prevent the rotations of the wound portions b1 and b2. The rotation stop mechanism can switch between the rotation stopped state and the rotation allowed state by controlling the screw 23.

FIG. 19 is a perspective view showing a toothed surface 210 capable of stopping the rotation of the reel portions 20. In the twelfth embodiment (FIG. 18A to FIG. 18C), the bottom portions p11 and p21 of the respective ports are brought into contact with the corresponding rotary gears 32, whereby the rotation of the reel portions 20 is stopped. From the viewpoint of ensuring the stop of the rotation of the reel portions 20, a toothed surface can be formed on the bottom portions p11 and p21 of the respective ports and the rotary gears 32. The effect of the stop of the rotation can be enhanced by engaging these toothed surfaces with each other. The toothed surface 210 is an example of such toothed surfaces. The toothed surface 210 includes first surfaces 212 arranged at predetermined angle intervals in the circumferential direction, and second surfaces 214 arranged each between two adjacent first surfaces 212. In the circumferential direction, the first surfaces 212 and the second surfaces 214 are alternately arranged. The first surfaces 212 are arranged at equal intervals in the circumferential direction. The second surfaces 214 are arranged at equal intervals in the circumferential direction. Each first surface 212 is an inclined surface. Each first surface 212 is inclined with respect to the axial direction and is inclined with respect to the circumferential direction. Each second surface 214 is parallel to the axial direction and is perpendicular to the circumferential direction.

FIG. 20 is a side view showing a state in which the toothed surface 210 engages with an opposed surface. The opposed surface is a toothed surface 220. The toothed surface 220 is obtained by transferring the toothed surface 210. The toothed surface 220 includes first surfaces 222 and second surfaces 224. In the circumferential direction, the first surfaces 222 and the second surfaces 224 are alternately arranged. The first surfaces 222 are arranged at equal intervals in the circumferential direction. The second surfaces 224 are arranged at equal intervals in the circumferential direction. Each first surface 222 is an inclined surface. Each first surface 222 is inclined with respect to the axial direction and is inclined with respect to the circumferential direction. Each second surface 224 is parallel to the axial direction and is perpendicular to the circumferential direction.

As shown in FIG. 20, when the toothed surface 210 engages with the toothed surface 220 (hereinafter this state is referred to as an engaged state), the first surfaces 212 and corresponding first surfaces 222 are in surface contact with

16

each other, and the second surfaces 214 and corresponding second surfaces 224 are in surface contact with each other.

For example, in the embodiment of FIG. 18A to FIG. 18C, the toothed surface 210 may be formed on the upper surface 5 of each of the bottom portions p11 and p21 of the respective ports, and the toothed surface 220 may be formed on the lower surface of each rotary gear 32. The contact between the toothed surface 210 and the toothed surface 220 rotates the reel portion 20 in the reel-in direction. That is, when the toothed surface 210 and the toothed surface 220 are brought into contact with each other in a state where the positional relationship in the circumferential direction between these surfaces is different from the above-described engaged state, the contact between the inclined surfaces (contact between first surfaces 212 and corresponding first surfaces 222) causes a rotational moment that rotates the reel portion 20 such that these surfaces are brought about the engaged state. This rotation moment rotates the reel portion 20 in the reel-in direction. The toothed surface 210 and the toothed surface 220 constitute a locking and tightening mechanism 226 configured to rotate the reel portion 20 in the reel-in direction and to prevent further rotation of the reel portion 20. The locking and tightening mechanism 226 enhances the effect of preventing the slack the third part wt3.

Advantageous Effect

The golf club heads shown in the above-described embodiments of the present disclosure exhibit the following 30 advantageous effects.

The weight distribution of the weight member wt can be changed by changing the ratio of the amount of the weight member wt wound around the first wound portion b1 to the amount of the weight member wt wound around the second wound portion b2. The position of the center of gravity of the head can be shifted toward the first wound portion b1 by increasing the amount of the weight member wt wound around the first wound portion b1, that is, by increasing the amount of the first part wt1. The position of the center of gravity of the head can be shifted toward the second wound portion b2 by increasing the amount of the weight member wt wound around the second wound portion b2, that is, by increasing the amount of the second part wt2. The amount of the weight member wt wound around the first wound portion b1 and the amount of the weight member wt wound around the second wound portion b2 each are also referred to as a weight-member wound amount. The position of the center of gravity of the head is adjusted by changing the weight-member wound amount of at least either the first part wt1 or the second part wt2.

The position of the first wound portion b1 and the position of the second wound portion b2 can be freely set. This can realize a desired adjustment of the position of the center of gravity of the head. For example, as shown in the head 2 of FIG. 2, when the first wound portion b1 is disposed on the toe side, and the second wound portion b2 is disposed on the heel side, then the position of the center of gravity of the head can be adjusted in the toe-heel direction. For example, as shown in the head 190 of FIGS. 16A and 16B, when the first wound portion b1 is disposed in the crown portion 6, and the second wound portion b2 is disposed in the sole portion 8, then the position of the center of gravity of the head can be adjusted in the up-down direction. Since the position of the first wound portion b1 and the position of the second wound portion b2 can be set independently of each other, various adjustments can be made. The degree of freedom of the adjustment can be further increased by

disposing a projection(s) in addition to the first wound portion **b1** and the second wound portion **b2**.

The position of the center of gravity of the head can be shifted in various directions because of the degree of freedom in the arrangement of the first wound portion **b1**, the second wound portion **b2**, and the projection(s). In the embodiment shown in FIG. 2, the position of the center of gravity of the head can be shifted in the toe-heel direction. In the embodiment of FIG. 16A and FIG. 16B, the position of the center of gravity of the head can be shifted in the up-down direction. In the embodiment of FIG. 10, the position of the center of gravity of the head can be shifted in the face-back direction and the toe-heel direction. For example, in the embodiment of FIG. 2, the position of the first wound portion **b1** in the face-back direction may differ from the position of the second wound portion **b2** in the face-back direction. In this case, the position of the center of gravity of the head can be shifted in the toe-heel direction and the face-back direction. For example, in the embodiment of FIG. 16A and FIG. 16B, the position of the first wound portion **b1** in the toe-heel direction may differ from the position of the second wound portion **b2** in the toe-heel direction. In this case, the position of the center of gravity of the head can be shifted in the up-down direction and the toe-heel direction. Thus, various adjustments can be made. The weight member **wt**, which can be wound, enables a head to have various weight distributions because of the flexibility of the weight member **wt**.

Two or more pairs of the first wound portion **b1** and the second wound portion **b2** may be provided. The degree of freedom in adjusting the position of the center of gravity of the head can be further increased by the two or more pairs of them. For example, in the head **180** of FIG. 15A and FIG. 15B, a first pair is disposed in the crown portion **6**, and a second pair is disposed in the sole portion **8**, which enables an adjustment with higher degree of freedom.

The weight member **wt** may be replaceable. For example, the weight member **wt** may be replaced with another weight member **wt** having a weight per unit length different from that of the former weight member **wt**. Further, two or more bundled weight members **wt** may be used. These configurations increase the degree of freedom of the adjustment.

The presence of the first port **p1** can prevent the first wound portion **b1** from protruding from the outer surface of the head. The presence of the second port **p2** can prevent the second wound portion **b2** from protruding from the outer surface of the head. The presence of the housing recess **p3** can prevent the third part **wt3** of the weight member **wt** from protruding from the outer surface of the head. These states in which those portions do not protrude from the head outer surface improve the appearance of the head and reduce air resistance. In addition, in the sole portion **8**, these states reduce ground resistance.

In the embodiment of FIG. 3A to FIG. 3C, each of the first wound portion **b1** and the second wound portion **b2** can rotate in the reel-in direction and the reel-out direction. Each of the first wound portion **b1** and the second wound portion **b2** has a rotational resistance both when rotated in the reel-in direction and when rotated in the reel-out direction. Neither the first wound portion **b1** nor the second wound portion **b2** rotates when a rotational force (moment) less than a predetermined threshold is applied. Each of the first wound portion **b1** and the second wound portion **b2** rotates when a rotational force equal to or greater than the threshold is applied. This configuration easily achieves a state (hereinafter referred to as a weight fixed state) in which the rotation

of the first wound portion **b1** and the rotation of the second wound portion **b2** are prevented while tension is applied to the third part **wt3**.

In the embodiment of FIG. 4A to FIG. 4C, each of the first wound portion **b1** and the second wound portion **b2** can rotate in the reel-in direction and the reel-out direction. Each of the first wound portion **b1** and the second wound portion **b2** has the ratchet mechanism. The ratchet mechanism can switch the rotation direction between the reel-in direction and the reel-out direction. This configuration easily achieves the weight fixed state in which the rotation of the first wound portion **b1** and the rotation of the second wound portion **b2** are prevented while tension is applied to the third part **wt3**.

In the embodiment of FIG. 5A and FIG. 5B, each of the first wound portion **b1** and the second wound portion **b2** is configured to perform an alternate action in which each of the first wound portion **b1** and the second wound portion **b2** is independently switched between the projecting position and the pushed-in position by each pushing of the first wound portion **b1** or the second wound portion **b2**. The rotation of the first wound portion **b1** and the rotation of the second wound portion **b2** are allowed when they are at the projecting position, and the rotation of the first wound portion **b1** and the rotation of the second wound portion **b2** are prevented when they are at the pushed-in position. This configuration easily achieves the weight fixed state in which the rotation of the first wound portion **b1** and the rotation of the second wound portion **b2** are prevented while tension is applied to the third part **wt3**. Furthermore, the first wound portion **b1** and the second wound portion **b2** can also be rotated by fingers when they are at the projecting position.

Not only the embodiment of FIG. 5A, 5B but also other embodiments may include the first wound portion **b1** and the second wound portion **b2** each have a switching mechanism capable of switching between a rotation allowed state and a rotation prevented state. In this case, for adjusting the position of the center of gravity of the head, the first wound portion **b1** and the second wound portion **b2** can be set to the rotation allowed state, and for achieving weight fixed state, the first wound portion **b1** and the second wound portion **b2** can be set to the rotation prevented state.

In the embodiments of FIG. 3A to FIG. 3C, FIG. 4A to FIG. 4C, FIG. 5A, FIG. 5B, and FIG. 18A to FIG. 18C, the first wound portion **b1** and the second wound portion **b2** each have a rotation regulating mechanism that regulates the rotation of the first wound portion **b1** or the rotation of the second wound portion **b2** in the reel-out direction. The rotation resistance mechanism **30** (FIG. 3C), the ratchet mechanism **40** (FIG. 4C), the rotation prevention mechanism **50** (FIG. 5A, FIG. 5B), and the rotation stop mechanism (FIG. 18A, FIG. 18B) are examples of the rotation regulating mechanism. The rotation regulating mechanism can easily achieve the weight fixed state in which the third part **wt3** has no slack. Furthermore, in the embodiments shown in FIG. 18A and FIG. 18B, since the two kinds of rotation regulating mechanisms are provided, the slack of the third part **wt3** can be effectively suppressed.

As described above, the locking and tightening mechanism **226** shown in FIG. 19 and FIG. 20 may be applied to the embodiment of FIG. 18A and FIG. 18B, for example. Further, the locking and tightening mechanism **226** can be used instead of the rotation prevention mechanism **50** in the embodiment of FIG. 5A and FIG. 5B. The locking and tightening mechanism **226** can effectively suppress the slack of the third part **wt3**.

As shown in the head **100** of FIG. 7, the first part **wt1** and the second part **wt2** can be visually recognized from the

outside of the head by imparting transparency to the first wound portion **b1** and the second wound portion **b2**. In the head **110** of FIG. 8, the first part **wt1** and the second part **wt2** can be visually recognized from the outside of the head through the notch **20a**. These structures allow the user to see the wound amount of first part **wt1** and the second part **wt2**.

When at least either the first part **wt1** or the second part **wt2** can be visually recognized, the wound amount of the other one can be assumed. From this viewpoint, a head that satisfies the following item (a) or (b) is preferable. As in the embodiments shown in FIG. 7 and FIG. 8, a head that satisfies the following (a) and (b) is more preferable.

(a) a head configured such that the first part wound around the first wound portion is visually recognized from the outside of the head

(b) a head configured such that the second part wound around the second wound portion is visually recognized from the outside of the head

The configuration in which the first part **wt1** and the second part **wt2** can be visually recognized from the outside of a head can be achieved by not only the transparency or notch, but also projecting the wound portions **b1** and **b2** from the head outer surface, and widening a gap between the wound portions **b1** and **b2** and the ports **p1** and **p2**, for example.

As shown in the heads **120**, **130**, and **140** of FIG. 9 to FIG. 11, one or more projections around which the third part **wt3** of the weight member **wt** is wound may be provided in addition to the first wound portion **b1** and the second wound portion **b2**. The degree of freedom of adjustment is further increased by winding the weight member **wt** around the one or more projections in addition to the first wound portion **b1** and the second wound portion **b2**.

As shown in the head **140** of FIG. 11, the first wound portion **b1**, the second wound portion **b2**, and the third part **wt3** of the weight member **wt** may protrude from the head outer surface. The head **140** does not need to include a first port **p1**, a second port **p2**, or a housing recess **p3**. Accordingly, the head body **h1** is easily formed, and the degree of freedom in designing the head body **h1** is increased. In addition, when the first wound portion **b1** and the second wound portion **b2** protrude from the head outer surface as in the head **150** of FIG. 12, the first wound portion **b1** and the second wound portion **b2** can be rotated by fingers without using a tool.

As in the head **150** of FIG. 12, the first wound portion **b1** and the second wound portion **b2** may be non-rotatable. In this case, for example, the weight member **wt** can be wound around the first wound portion **b1** and the second wound portion **b2** with fingers. Either the first wound portion **b1** or the second wound portion **b2** may be rotatable, and the other may be non-rotatable. From the viewpoint of the adjustability of the position of the center of gravity of the head, each of the first wound portion **b1** and the second wound portion **b2** is preferably rotatable in the reel-in direction and the reel-out direction.

In the head **170** of FIG. 14, the cover member **172** is provided. This configuration can protect the first wound portion **b1**, the second wound portion **b2**, and the third part **wt3** from the intrusion of foreign matters. In addition, this configuration prevents the first wound portion **b1**, the second wound portion **b2**, and the third part **wt3** from catching grass and the like. The cover member **172** may have transparency. This transparency allows the first wound portion **b1**, the second wound portion **b2**, and/or the third part **wt3** covered with the cover member **172** to be visually recognized from the outside of the head.

In a head having a large volume, the first wound portion **b1** and the second wound portion **b2** can be located farther away from each other, and the degree of freedom in the positions of the first wound portion **b1** and the second wound portion **b2** is increased. Accordingly, the adjustable range and the degree of freedom in adjustment of the position of the center of gravity of the head are increased. From these viewpoints, a hollow head having a hollow portion is preferable. From the same viewpoint, the volume of the head is preferably greater than or equal to 100 cc, more preferably greater than or equal to 200 cc, still more preferably greater than or equal to 300 cc, still more preferably greater than or equal to 350 cc, still more preferably greater than or equal to 400 cc, and yet still more preferably greater than or equal to 420 cc. From the viewpoint of golf rules, the head volume is preferably less than or equal to 470 cc, and more preferably less than or equal to 460 cc.

Regarding the above-described embodiments, the following clauses are disclosed.

Clause 1

A golf club head having a face portion, a crown portion and a sole portion, the golf club head including:

a weight member that is configured to be wound;
a first wound portion around which a first part of the weight member is to be wound; and
a second wound portion that is disposed apart from the first wound portion and around which a second part of the weight member is to be wound, wherein
a position of a center of gravity of the golf club head is adjusted by changing a weight ratio of the first part to the second part.

Clause 2

The golf club head according to clause 1, wherein at least either the first wound portion or the second wound portion is rotatable in a reel-in direction and a reel-out direction.

Clause 3

The golf club head according to clause 1 or 2, wherein the first wound portion and the second wound portion are rotatable in a reel-in direction and a reel-out direction.

Clause 4

The golf club head according to clause 3, wherein each of the first wound portion and the second wound portion includes a rotation regulating mechanism that regulates the rotation of the first wound portion or the second wound portion in the reel-out direction.

Clause 5

The golf club head according to any one of clauses 1 to 4, wherein the golf club head further includes:
a first port that houses the first wound portion including the first part;
a second port that houses the second wound portion including the second part; and
a housing recess that houses a third part that is a part of the weight member other than the first part or the second part.

21

Clause 6

The golf club head according to any one of clauses 1 to 5, wherein the first wound portion and the second wound portion are disposed in the sole portion.

Clause 7

The golf club head according to any one of clauses 1 to 5, wherein the first wound portion and the second wound portion are disposed in the crown portion.

Clause 8

The golf club head according to any one of clauses 1 to 5, wherein the first wound portion is disposed in the sole portion, and the second wound portion is disposed in the crown portion.

Clause 9

The golf club head according to any one of clauses 1 to 8, wherein the golf club head satisfies the following (a) and/or (b):

(a) the golf club head is configured such that the first part wound around the first wound portion is visually recognized from an outside of the golf club head; and

(b) the golf club head is configured such that the second part wound around the second wound portion is visually recognized from the outside of the golf club head.

Clause 10

A golf club head having a face portion, a crown portion and a sole portion, the golf club head including:

a weight member that is configured to be wound; a first wound portion around which a first part of the weight member is to be wound; and

a second wound portion that is disposed apart from the first wound portion and around which a second part of the weight member is to be wound, wherein

a position of a center of gravity of the golf club head is adjusted by changing at least either a wound amount of the first part or a wound amount of the second part.

10 The above descriptions are merely illustrative and various modifications can be made without departing from the principles of the present disclosure.

The terminology used in the description of the various described embodiments herein is for the purpose of describing particular embodiments only and is not intended to be limiting. The use of the terms "a", "an", "the", and similar referents in the context of throughout this disclosure (especially in the context of the following claims) are to be construed to cover both the singular and the plural, unless 15 otherwise indicated herein or clearly contradicted by context. As used throughout this disclosure, the word "may" is used in a permissive sense (i.e., meaning "having the potential to"), rather than the mandatory sense (i.e., meaning "must"). Similarly, as used throughout this disclosure, the terms "comprising," "having," "including," and "containing" are to be construed as open-ended terms (i.e., meaning "including, but not limited to,") unless otherwise noted.

What is claimed is:

- 30 1. A golf club head including a face portion, a crown portion and a sole portion, the golf club head comprising: a weight member that is configured to be wound; a first wound portion around which a first part of the weight member is to be wound; and a second wound portion that is disposed apart from the first wound portion and around which a second part of the weight member is to be wound, wherein a position of a center of gravity of the golf club head is adjusted by changing a weight ratio of the first part to the second part.
- 40 2. The golf club head according to claim 1, wherein at least either the first wound portion or the second wound portion is rotatable in a reel-in direction and a reel-out direction.
- 45 3. The golf club head according to claim 1, wherein the first wound portion and the second wound portion are rotatable in a reel-in direction and a reel-out direction.
- 50 4. The golf club head according to claim 3, wherein each of the first wound portion and the second wound portion includes a rotation regulating mechanism that regulates the rotation of the first wound portion or the second wound portion in the reel-out direction.
- 55 5. The golf club head according to claim 1, wherein the golf club head further includes: a first port that houses the first wound portion including the first part; a second port that houses the second wound portion including the second part; and a housing recess that houses a third part that is a part of the weight member other than the first part or the second part.
- 60 6. The golf club head according to claim 1, wherein the first wound portion and the second wound portion are disposed in the sole portion.
- 65 7. The golf club head according to claim 1, wherein the first wound portion and the second wound portion are disposed in the crown portion.

23

8. The golf club head according to claim 1, wherein the first wound portion is disposed in the sole portion, and the second wound portion is disposed in the crown portion.

9. The golf club head according to claim 1, wherein the golf club head satisfies the following (a) and/or (b):

(a) the golf club head is configured such that the first part wound around the first wound portion is visually recognized from an outside of the golf club head; and

(b) the golf club head is configured such that the second part wound around the second wound portion is visually recognized from the outside of the golf club head.

10. The golf club head according to claim 1, wherein the golf club head further includes:

a first port that houses the first wound portion including the first part; and

a second port that houses the second wound portion including the second part, wherein

the first wound portion is housed in the first port so as not to protrude from an outer surface of the golf club head, and

the second wound portion is housed in the second port so as not to protrude from the outer surface of the golf club head.

11. A golf club head including a face portion, a crown portion and a sole portion, the golf club head comprising:

a weight member that is configured to be wound;

a first wound portion around which a first part of the weight member is to be wound; and

a second wound portion that is disposed apart from the first wound portion and around which a second part of the weight member is to be wound, wherein

a position of a center of gravity of the golf club head is adjusted by changing at least either a wound amount of the first part or a wound amount of the second part.

12. The golf club head according to claim 11, wherein at least either the first wound portion or the second wound portion is rotatable in a reel-in direction and a reel-out direction.

13. The golf club head according to claim 11, wherein the first wound portion and the second wound portion are rotatable in a reel-in direction and a reel-out direction.

14. The golf club head according to claim 13, wherein each of the first wound portion and the second wound portion includes a rotation regulating mechanism that regu-

24

lates the rotation of the first wound portion or the second wound portion in the reel-out direction.

15. The golf club head according to claim 11, wherein the golf club head further includes:

a first port that houses the first wound portion including the first part;

a second port that houses the second wound portion including the second part; and

a housing recess that houses a third part that is a part of the weight member other than the first part or the second part.

16. The golf club head according to claim 11, wherein the first wound portion and the second wound portion are disposed in the sole portion.

17. The golf club head according to claim 11, wherein the first wound portion and the second wound portion are disposed in the crown portion.

18. The golf club head according to claim 11, wherein the first wound portion is disposed in the sole portion, and the second wound portion is disposed in the crown portion.

19. The golf club head according to claim 11, wherein the golf club head satisfies the following (a) and/or (b):

(a) the golf club head is configured such that the first part wound around the first wound portion is visually recognized from an outside of the golf club head; and

(b) the golf club head is configured such that the second part wound around the second wound portion is visually recognized from the outside of the golf club head.

20. The golf club head according to claim 11, wherein the golf club head further includes:

a first port that houses the first wound portion including the first part; and

a second port that houses the second wound portion including the second part, wherein

the first wound portion is housed in the first port so as not to protrude from an outer surface of the golf club head, and

the second wound portion is housed in the second port so as not to protrude from the outer surface of the golf club head.

* * * * *
